US0D1112279S

(12) United States Design Patent (10) Patent No.: US D1,112,279 S
(45) Date of Patent: * Feb. 10, 2026

(54) DISPLAY SCREEN OR PORTION THEREOF
WITH GRAPHICAL USER INTERFACE

CLAIM

(52) U.S. Cl.

The ornamental design for a display screen or portion thereof with graphical user interface as shown and described.

USPC D14/485

DESCRIPTION

(58) Field of Classification Search

The file of this patent contains at least one drawing/photograph executed in color. Copies of this patent with color drawing(s)/photograph(s) will be provided by the Office upon request and payment of the necessary fee.

USPC ..... D14/485—495
CPC G06F 3/048; G06F 3/0481; G06F 3/0482;
